PROPELLER DEICING MECHANISM

Jack H. Sheets, Verona, N. J., assignor to Curtiss-Wright Corporation, a corporation of Delaware

Application April 19, 1947, Serial No. 742,562

10 Claims. (Cl. 244—134)

1

This invention relates to de-icing equipment for aeronautical propellers and is concerned particularly with improvements in means for removing propeller ice by electrical resistance heaters.

Various arrangements have been proposed and are in use for de-icing the blades of aeronautical propellers by the use of electrical resistance heaters. Such heaters usually take the form of blankets or shoes applied to the leading edges of propeller blades, either externally of the blade or internally when the blade is hollow, the blankets incorporating resistance elements of wire, conductive rubber or other suitable material. Electrical power is fed to the heaters from a power source either carried by the propeller or carried by the aircraft with which the propeller is associated. When resistance heaters are applied to the blades of controllable pitch propellers, it is necessary to provide a movable or flexible electrical conductive system to lead electrical power from the propeller hub to the propeller blade. It is one of the objects of this invention to provide an improved means for conducting electrical power from a propeller hub to a variable pitch propeller blade.

Among the various problems associated with propeller de-icing by electrical heaters, is one to protect the propeller against unbalance due to non-uniform ice accretion on the propeller blades. If de-icing blankets or shoes are used on each of several blades of a propeller, it is essential that all shoes have the same de-icing effect. Should one of the shoes fail in any way, and should the heating power remain on, the blade having the failed shoe will accumulate ice while other blades of the propeller are properly de-iced. A very small accumulation of ice on one blade, while the other blades are free of ice, will cause an undesirable propeller unbalance.

It is a further object of this invention to provide safety means by which uniformity of de-icing power will be assured for all blades of a propeller. Still another object of the invention is to provide an electrical protective system which is responsive to an unbalanced electrical heating load to disconnect the heating power from the de-icing shoes. Such disconnection, while preventing further de-icing of the propeller blades even while icing conditions are prevalent, minimizes the hazard of propeller unbalance which may be a greater hazard than the lack of de-icing heat. A further object of the invention is to provide a heating power distributing system for multi-blade propellers

2

which will assure consistent operation of the de-icing equipment under all conditions likely to be encountered in service.

While certain embodiments of the invention have been chosen for illustration in the drawings, which are described in the annexed specification, it is to be understood that the scope of the invention is not limited by the disclosure of the drawings, except as such limitations may be implied in the annexed claims.

In the drawings,

Fig. 1 is a schematic diagram of one embodiment of an electrical propeller de-icing system;

Fig. 1A is a diagram of an alternative portion 15 of the system of Fig. 1;

Fig. 2 is a schematic diagram of an alternative arrangement of an electrical propeller de-icing system;

Fig. 3 is a fragmentary side elevation, partly 20 in section, of a propeller hub incorporating one of the features of the invention and comprising a section on the line 3—3 of Fig. 4, and

Fig. 4 is a section on the line 4—4 of Fig. 3.

Referring first to Fig. 1, an aircraft propeller hub is indicated at 10, the hub having a plurality of blade sockets one of which is shown at 11, from which propeller blades 12 extend outwardly, the blades 12 being journaled in the sockets 11 for pitch variation in flight. A power unit is indicated at 14, carrying a reversible electric motor connected, in a manner well known in the art, to the propeller blades for changing their pitch. Power for the electric motor, for increasing pitch, decreasing pitch, feathering, unfeathering, reversing pitch and unreversing pitch is provided through a plurality of slip rings 16 which are engaged by brushes 18 non-rotatably secured to a power plant and provided with electrical power from a power source 40 through an appropriate control system. The several switch elements 20 associated with the power unit 14 operate in conjunction with variation in propeller pitch to terminate pitch changing movement at predetermined pitch limits. The details of the pitch changing power supply and control are not germane to this invention since the provisions of the invention are usable with controllable pitch propellers of any type.

50 Two additional slip rings 22 and 24 are provided in conjunction with the slip ring assembly 16, these rings being engaged respectively by brushes 26 and 28 respectively connected to a protective relay unit 30 through a wire 32, and 55 to ground through a wire 34.

It will be assumed for the moment that electrical de-icing power is supplied to the wire 32. Each propeller blade carries an electrical resistance heater in the form of a shoe 36 secured around the leading edge of the propeller blade 12. The terminals of the heater 36 are directly connected to slip rings 38 and 40 embracing and secured to the shank of the blade 12, in insulated relation thereto. The propeller hub carries an extension 42 to the outer end of which a brush block 44 is secured having brushes 46 and 48 respectively engaging the blade slip rings 38 and 40. The brushes 46 and 48 are directly connected to the slip rings 22 and 24. In the preferred embodiment, the blade heater shoes 36 on the several blades are connected in parallel, all receiving de-icing power from the slip rings 22 and 24. However, the de-icing shoes 36 might likewise be connected in series. Alternatively, as shown in Fig. 1A, the propeller blades 12 may be provided with streamlined cuffs 50 embracing their shank ends, the cuffs being provided with heater shoes 52 similar in character to the shoes 36. Preferably, the shoes 52 and 36 of the cuffs and blades are serially connected, both receiving power from the slip rings 38 and 40. If it should be found convenient to do so, the shoes 52 and 36 could be connected in parallel. Alternatively, additional slip rings might be provided so that the several cuff shoes on different blades could be connected in series and the several blade shoes on different blades connected in series, the two sets of shoes being parallel-connected to the power slip rings 22 and 24. Any preferred connecting arrangement may be used for the several cuff and blade de-icing shoes and power may likewise be provided for a spinner de-icing boot if such a device is deemed desirable.

Where a plurality of de-icing shoes are used on different blades of a propeller, there is always a possibility, though not a probability, that one or another of such shoes might fail by fracture of the resistance wires within the shoe or by failure of one or more of the electrical connections conducting power to the shoes, or by other causes. Should a failure of any one shoe occur, it becomes ineffective for de-icing the propeller blade and ice can accumulate thereon while other blades are being de-iced. This sets up an unbalanced condition in the propeller which may result in excessive vibration in the propeller system, failure of the propeller, or failure in some form of the power plant and the aircraft. It is highly desirable therefore to guard against the possibility of propeller unbalance and to this end, the protective relay unit 30 is incorporated in the de-icing power supply to disconnect the power supply should an unusual electrical disturbance occur in the de-icing system.

The several de-icing shoes of any propeller system will have a definite current consumption within reasonable limits when operating normally. Should a partial or complete short circuit occur in any part of the system, the current consumption rises materially. Should an open circuit or a partial open circuit occur in the shoe circuits, current to the de-icing shoes will be reduced. Any form of electrical failure in the de-icing system may be expected to cause either an increase or a decrease in current supply as above indicated. Accordingly, the protective unit 30 comprises a device which is responsive to deviations in current from the normal value and range of current which may be expected for proper operation of the de-icing shoes.

In the unit 30 heating power is supplied from a bus 56 through a fuse or breaker 57 to one of two points of a normally open switch 58, the other point being connected through a wire 59 to the juncture of two windings 60 and 62 of a balanced relay 64. The winding 62 is a current coil whose other end leads to a terminal 66 to which the power lead 32, to the propeller, is connected. The coil 62 is so designed as to have a certain number of ampere turns based upon the normal current consumption and the impressed voltage. The coil 60 is a voltage coil which passes small current but which has a number of ampere turns based upon the impressed voltage and the current flow through the coil, substantially equal to the ampere turns in the coil 62. The two coils 60 and 62 produce opposed magnetic fields when normally energized to the end that no magnetic flux will appear in a core 67 of the relay. The remote end of the voltage coil 60 is connected to one point of a normally open switch 68 and through a variable resistor 70 to ground. The resistor 70 affords a calibration of the current flow through the coil 60 whereby its effect in magnetizing the core 67 may be balanced against the current coil 62 and calibrated and adjusted over a range of current limits desired for the de-icing system.

Should the de-icing resistors decrease in resistance as by a partial short circuit, current flow in the current coil 62 will increase while the effect of the coil 60 remains constant or decreases slightly, thereby magnetizing the core 67 and closing the relay switch 68 for a purpose which will become apparent. Also, should an open circuit or a partial open circuit occur in the de-icing heater system, the current flow through the current coil 62 will decrease and thereby the voltage coil 60 will magnetize the core 67 and close the switch 68. Thus, any deviations beyond established limits of current flow in the de-icing system will cause closure of the switch 68.

This switch 68 is connected to a polarized relay 71 provided with a two-position switch arm 72 contactable with points 74 or 76. Normally, the switch arm is engaged with the point 74 which in turn is connected to a relay coil 78 which serves when energized to close the switch 58 through which power is fed from the bus 56 to the heater power lead 32. The switch 72, point 74 and relay coil 78 comprise a portion of a control circuit, the switch 72 being connected, through a terminal 80 to an interrupter switch 82 driven by a motor 84, the switch and motor being provided with operating energy through a switch 86 and through a fuse or breaker 88 from a power bus 90.

When the switch 86 is in the position shown, the motor 84 will operate, rotating the interrupter switch 82 to provide power pulses in sequence to the several switch points such as 91, one of which as at 92, is connected to the terminal 80 of the protective unit 30. Other points 91 of the interrupter switch 82 may be connected to other propeller systems in the aircraft or to other circuit systems. When there is a power pulse from the switch 82, the relay coil 78 will be energized through the switch 72 and the point 74 to close the switch 58 and to provide de-icing power as previously described. Should the de-icing shoe system be faulty, the balanced relay 64 will close the normally open switch 68, energizing the polarized relay 71 and throwing its switch arm 72 from the contact 74 to the contact 76. This opens the circuit to

the relay coil 78 thus permitting the switch 52 to remain open and preventing continued flow of de-icing power to the heater system until resetting of the switch 72 is accomplished. The switch 72 when engaged with the contact point 76, may if desired, energize a pilot lamp 94 serving as an indication to the air crew that the de-icing system has ceased operation.

The switch 86 may then be opened from its contact 86a disconnecting the control circuit and stopping operation of the motor 84 and the interrupter switch 82. The system may be reset for normal operation by closing the switch 86 on the contact 86b which connects to a relay multiple switch 98, energizing the relay coil 98 which closes a switch 100 passing control power to a terminal 102 on the protective unit 30 and thence to the coil of the polarized relay 71. The action just described energizes the coil of the relay 71 in reverse polarity to that which occurred when the relay was energized to throw the switch 72 from the point 74 to the point 76. Thus, with this reverse energization, the switch 72 is thrown back from the point 76 to the point 74, restoring the protective relay system 30 to a condition where it will operate in normal fashion to pass power from the bus 56 to the propeller de-icing shoes. After this resetting operation, the switch 86 may again be connected to the point 86a and the de-icing system is restarted for normal operation. If the difficulty in the propeller heater system has been corrected, normal operation will be resumed. If the difficulty still exists, or if another difficulty should occur, the protective relay system 30 will again terminate operation of the system in the manner heretofore described until such time as the de-icing system has been restored to proper condition.

Fig. 2 shows an alternative arrangement of the de-icing system which, while similar in many respects to the arrangement of Figs. 1 and 1A, incorporates certain modifications adapting it for use with propellers having four or more blades wherein the blades are arranged in opposite pairs. The Fig. 1 system is adapted for use with fans or propellers having two or three, or any odd number of blades where the entire de-icing power is cut off upon the failure of a de-icing shoe circuit in any one of the blades.

In Fig. 2, 112 indicates one of a pair of opposite blades on a propeller hub 114, while 116 represents one blade of another pair of opposed blades, disposed in angular relation to the first pair. For instance, the blade 116 in a four-bladed propeller would lie at 90° to the blade 112, the break 118 in the propeller hub signifying that the blade 116 actually does not lie 180° from the blade 112. In this system, three de-icing slip rings 120, 122 and 124 are provided. The slip ring 120 and its associated brush provide power transfer to the propeller, the slip ring being connected to a hub mounted brush 130 contacting a blade slip ring 132 serving the de-icing shoe on the blade 116 and its associated cuff. The return circuit is accomplished through the blade slip ring 134, the hub brush 136, the slip ring 124 through brush 126 to a power return 128. The blade opposite to the blade 116 will preferably be parallel-connected to the same hub slip rings 120 and 124. Shoes on other pairs of opposite blades and cuffs such as 112 will receive de-icing power from the hub slip ring 122 through hub brushes and blade slip rings similar to those previously described, the return circuit

being made to the hub slip ring 124. Thus it will be seen that there are two de-icing power circuits served by power leads 140 and 142 leading respectively from terminals 144 and 146 of protective relay control units 148 and 150 to the brushes for slip rings 120 and 122. The units 148 and 150 are identical if desired and similar to the protective relay unit 30 of Fig. 1.

The same reference characters are applied to the units 148 and 150 as were applied to the unit 30 so that a reading of the previous description will apply in connection with Fig. 2 in all important respects. However, the malfunction indicating lamp 94 may if desired be connected to both switch points 76 of the units 148 and 150 whereby a failure of either de-icing circuit will be indicated on the same lamp.

The same type of interrupter switch 82 may be utilized in the system of Fig. 2 as was described in connection with Fig. 1, different interrupter contacts being utilized to provide control impulses to the two different protective units 148 and 150, as for instance through the wires 152 and 154. The main switch for starting operation of the de-icing system is indicated at 86, this switch serving as in Fig. 1 to start the interrupter motor 84 when the switch is turned on. The switch may also be thrown to the reset position 86b as previously described to close the reset relay 96, energizing the polarized relays 71 in the protective units to restore the system for normal operation.

It is again noted that several propellers each incorporating de-icing systems may be included in a single installation and the same primary control switches are arranged to operate all such systems coincidentally. This accounts for the unconnected ends of conductors shown in the diagram which normally lead to other installations similar to the installation disclosed in detail.

A system such as that shown in Fig. 2 may readily be applied to propellers having six blades or more or to dual rotation propeller systems, the changes necessary for adaptation of the system being deemed to come within the scope of skill in the art. This type of system may also be applied to segmental shoes on blading wherein more than one shoe is installed on a blade, the number of blades in the propeller then being immaterial. Also, the system is applicable to multi-bladed fans or impellers, opposite groups of blades being connected in the same circuit system.

The interrupter switch 82 may be dispensed with, if desired, so that de-icing current is passed continuously through the de-icing shoes of the propeller blades when the system is turned on. The purpose of the interrupter system is to cycle de-icing current of fairly high density to the propeller blades for short periods of time to cause substantial heating of the blades to remove ice accretion thereon. This arrangement has been found very effective as distinguished from a system in which a current of low density is supplied to the blade de-icing shoes on a continuous basis. The cycling system involving the use of the interrupter switch 82 is not specifically a part of the invention, and its use in connection with the invention is optional.

Referring now to Figs. 3 and 4, a particular structural arrangement of a propeller hub and blade is shown, embodying blade slip rings and hub carried brushes. Reference characters previously used in connection with Fig. 1 are applied where applicable. The propeller hub 13, normally mounted on a propeller shaft, includes an integral coaxial cylinder 160 over which is assembled a

ring member 162 having radially extending arms 42, one for each blade, integral therewith. The member 162 is secured to the hub 10 and the several slip rings 22, 24 and 46, the rings being separated by insulating washers and bushings generally indicated at 164 are assembled over and secured to the cylinder 160. The member 162 includes a plurality of circumferentially spaced recesses 166 within which are disposed connector units 168 embraced by insulating material 170. Each slip ring such as 22 as shown is connected to one connector 168 by a conducting screw 172. At the top of each arm 42, the brush block 44 is secured by screws 174 (Fig. 4) the brush block including brush carriers 176 within which the spring pressed brushes such as 46 and 48 are slidably contained. Preferably, the brushes are in multiple sets to improve slip ring contact, the brushes 48 for instance being interconnected and being connected to the appropriate connector unit 168 by a conductive screw 178.

One connection between the brushes 48 and the slip ring 22 is shown in Fig. 3, and the same type of construction is preferred to connect the brushes 46 to its slip ring and to connect other brushes on the propeller hub to the appropriate slip rings when the blade shoes are parallel-connected. If shoes are series connected, solution of the problem of connections may be made by the skilled designer. Each of the screws 178 is insulated from the hub structure by an embracing sleeve 180 passing through the brush block and the ring extension 42 to the connector 168.

On the shank of the blade 12, a pair of semi-circular insulating bushing elements 184 are assembled, these elements including circumferential channels for the reception of the slip rings 38 and 40. The bushings and slip rings are assembled on the blade beneath the usual narrow ring 186 integral with the blade, this ring preventing outward displacement of the slip ring assembly due to the effects of centrifugal force on the propeller blade. These rings 186 are also used for constraining blade embracing cuffs against the effect of centrifugal force and if cuffs are used, the insulating bushings 184 may be assembled around the blade shanks inboard of the blade cuffs. Since the maximum angular pitch change of a propeller blade is of the order of 120° between feathering position and reverse pitch position, the slip rings 38 and 40 may be in the form of split bands as shown in Fig. 4, the ends of the bands being secured to one another, around the insulating bushings 184, by screws 188 engaging lugs 190 riveted or otherwise secured to the slip ring elements. The ring clamping lugs 190 serve as convenient points of attachment of flexible conductors such as 192 which lead directly to the terminals of the blade or cuff de-icing shoes. In assembling the clamp slip rings on the propeller blade shanks, the clamp lugs 190 are disposed at such points on the circumference of the propeller blade shanks so that they will not interfere with the hub carried brushes 46 and 48 in any pitch position of the propeller blades between reverse pitch and feather. Slip ring or conductor bands need not necessarily embrace the blades—they may be segmental and may be secured to the blades by embracing straps or by other means.

It will be noted that the hub brush and blade slip ring arrangement above described avoids the need for carrying de-icing conductors through the propeller hub and minimizes electrical failure by rugged conductors and contacting arrangements. The slip ring system is highly de-

sirable where large pitch change angles are expected in the propeller. An alternative arrangement consists in the use of flexible pigtails leading from a hub carried junction block to the propeller blade shoes but such flexible pigtails are subject to mechanical failure particularly when they are made long enough to allow freedom of blade pitch change through as large an angle as 120°.

Though several embodiments illustrating the invention have been shown and described, it is to be understood that the invention may be applied in other and various forms. Changes may be made in the arrangements, without departing from the spirit of the invention. Reference should be had to the appended claims for definitions of the limits of the invention.

What is claimed is:

1. In a de-icing system for a propeller comprising a hub having a plurality of blades mounted therein, a blade heater circuit including an electrical heater on each blade, an electrical power supply for said heaters, said heaters normally drawing a certain current for a certain impressed potential, a switch in said blade heater circuit operable to disconnect and closable to connect said heaters relative to said power supply, and means responsive to deviations in heater current from said certain current, when said heaters are energized, to open said switch.

2. In a current control system for an electrical resistance de-icing heater in aircraft, said heater having a certain normal current consumption when operating normally, a power supply system normally providing substantially constant potential, a normally balanced solenoid having opposed current and voltage windings having normally equal ampere turns energized by heater power, a normally closed switch in said power supply, and means responsive to unbalance between the current and voltage windings to open said switch.

3. In a current control system for an electrical resistance de-icing heater in aircraft, said heater having a certain normal current consumption when operating normally, a power supply system normally providing substantially constant potential, a normally balanced solenoid having opposed current and voltage windings having normally equal ampere turns energized by heater power, a normally closed switch in said power supply, means responsive to unbalance between the current and voltage windings to open said switch and an electrical reset mechanism optionally operable to close said switch.

4. In a de-icing system for a propeller comprising a hub and cuffed blades mounted thereon, an electrical heater on each cuff, an electrical heater on each blade, the heaters of associated blades and cuffs being serially connected and the several blade and cuff heater series being parallel-connected, a power supply for said heaters, and means responsive to an under-supply of power to any one blade-cuff heater set to disconnect the power supply to the several parallel-connected blade-cuff heater sets.

5. In a de-icing system for a propeller comprising a hub and blades mounted thereon, an electrical heater on each blade, said heaters being parallel-connected, a power supply, and means responsive to an under-supply of power to any one blade heater to disconnect the several parallel-connected blade heaters from said power supply, the power connections from said supply to said blade heaters comprising hub-mount-

ed brushes and slip segments on the blades engaged by said brushes and connected to said heaters.

6. In a de-icing system for a propeller having a hub and blades mounted therein for pitch change, electrical resistance heaters on the blades having substantially constant resistance and consequently substantially constant current draw for a particular impressed potential, an electrical power supply for said heaters delivering power at said particular potential, a control circuit connecting said supply with the heaters, the control circuit including a normally closed switch connecting the power supply and the heaters, and means operatively connected to said switch to open same and energized by the current flowing through said switch, said means being responsive to material deviations in current from said substantially constant current draw to open said switch.

7. In a de-icing system for a propeller having a hub and blades mounted therein for pitch change, electrical resistance heaters on the blades having substantially constant resistance and consequently substantially constant current draw at a particular impressed potential, an electrical power supply for said heaters delivering power at said particular potential, means comprising slip connections between the hub and blades for conducting the electrical power from the hub to said blade heaters, a control circuit connecting said supply with the heaters through said slip connections, a normally closed switch connecting the supply with the heaters, and means operatively connected to said switch to open same and energized by the current flowing through said switch, said means being responsive to material deviations in said substantially constant current draw to open said switch.

8. In an aircraft propeller having four blades, 40 said blades being arranged in opposed pairs, an electrical heater on each blade, the heaters of each blade pair being connected together, a power source, connections from said power source to the heaters of one blade pair, connections separate from the first connections from said power source to another blade pair, the heater pairs of respective blade pairs having a substantially constant current consumption when energized at a substantially constant potential as provided 50 by said power source, a normally closed switch

in each set of connections, and means operatively connected to each said switch to open same and energized by the current in respective connections, each said means being responsive to material deviations in current consumption of respective heater pairs from said constant current consumption to open the respective switches.

9. In a de-icing system for a propeller comprising a hub and a blade mounted thereon, an electrical heater on said blade having substantially constant current consumption when energized at a substantially constant potential, an electrical power supply having an output at said potential, 15 a circuit connecting said supply with said heater including two serially connected switches, one of said switches being selectively operable, and means connected in said circuit and energized by said current, operatively connected to the 20 other of said switches to open same in response to material departure of said current consumption from said substantially constant current consumption.

10. In an aircraft de-icing system, an electrical heater on the aircraft having substantially constant current consumption when energized at a substantially constant potential, an electrical power supply having an output at said potential, 25 a circuit connecting said supply with said heater including two serially connected switches, one of said switches being selectively operable, and means connected in said circuit and energized by said current, operatively connected to the 30 other of said switches to open same in response to material departure of said current consumption from said substantially constant current consumption.
